(57) **CLAIM**

The ornamental design for an identification tab and plug for a reagent storage device, as shown and described.

DESCRIPTION

FIG. 1 is an enlarged front left perspective view of the identification tab and plug for a reagent storage device according to our present design;

FIG. 2 is an enlarged right end perspective view thereof;

FIG. 3 is an enlarged right elevation view thereof;

FIG. 4 is an enlarged left elevation view thereof;

FIG. 5 is a front elevation view thereof;

FIG. 6 is a rear elevation view thereof;

FIG. 7 is a top view thereof; and,

FIG. 8 is a bottom view thereof.
